(57) **CLAIM**

The ornamental design for a vehicle integrated display and mount, as shown and described.

DESCRIPTION

FIG. 1 is a left perspective view of a vehicle integrated display and mount;

FIG. 2 is a right perspective view thereof;

FIG. 3 is a front elevational view thereof;

FIG. 4 is a left side elevational view thereof;

FIG. 5 is a right side elevational view thereof; and,

FIG. 6 is a top elevational view thereof.

In the drawings, the broken lines depict a vehicle console and form no part of the claimed design.
